DESIGN FOR A FLOWER SUPPORT

Abraham Cooperstein, Brooklyn, N. Y.

Application January 14, 1935, Serial No. 54,843

Term of patent 3½ years

To all whom it may concern:

Be it known that I, Abraham Cooperstein, a citizen of the United States of America, residing at 3452 Bedford Avenue, Brooklyn, in the county of Kings and State of New York, have invented a new, original, and ornamental Design for a Flower Support, of which the following is a specification, reference being had to the accompanying drawing, forming a part thereof, which is a perspective front view of the flower support showing my new design.

My design comprises individual flower supports each consisting of a stem having a bulb at its free end, the stems being ridged throughout their lengths.

I claim:

The ornamental design for a flower support as shown and described.

ABRAHAM COOPERSTEIN.
